HANDLE FOR FORKS, &c.

No. 18,387.

Patented June 12, 1888.

Fig. 2.

Fig. 1.

UNITED STATES PATENT OFFICE.

GEORGE W. SHIEBLER, OF BROOKLYN, NEW YORK.

DESIGN FOR A HANDLE FOR FORKS, &c.

SPECIFICATION forming part of Design No. 18,387, dated June 12, 1888.

Application filed April 9, 1888. Serial No. 270,147. Term of patent 7 years.

To all whom it may concern:

Be it known that I, GEORGE W. SHIEBLER, of Brooklyn, in the county of Kings and State of New York, have invented a Design for the Handles of Forks, Spoons, and Similar Articles, of which the following is a specification.

My new and original design relates to that style of ornamentation called "Rococo," which style of ornamentation was in vogue during the sixteenth century and the time of Louis XIV. of France.

My design and ornamentation relate to the handles of forks, spoons, knives, and various forms of ladles, and is especially adapted for use in sterling silverware and silver-plated ware, the design consisting of leaves, scrolls, shells, and gadroon-scroll or ogee-curved ornaments, as hereinafter set forth.

In the drawings, Figure 1 is a face view of the handle of a fork, and Fig. 2 is a back view of the same.

The outline or edge surface of the handle is shown in the raised gadroon-scroll or ogee-curved ornaments *a*, and scrolls *b*, and the leaf-scroll *b'*, the edge of the handle or outline conforming to these curved and scroll ornaments. The face of the handle, Fig. 1, is ornamented between the scrolls in raised leaf-patterns at *c*, and the back of the handle, Fig. 2, is ornamented in raised leaf-patterns at *c'*. The face of the handle, Fig. 1, is also ornamented between the scrolls in the raised shell-scroll pat-

terns *d*, and the back of the handle, Fig. 2, is also ornamented by the raised shell-scroll patterns *d'*. The shell ornament *e* forms the extreme end of the handle, and the central portion of the end of the face in Fig. 1 is made plain without ornamentation, the same being adapted for the engraving of the name or monogram. The portion of the fork, Fig. 2, back of the tines is ornamented by raised interwoven bands *i*, running from the tines backward, two of said bands joining with two of the gadroon scrolls or ogee curves *a*.

I claim as my invention—

1. The design of the handle for forks, spoons, &c., consisting in the scrolls, the gadroon scrolls or ogee curves forming the outline or edge surface of the handle, and the leaves and shell-patterns raised upon the face of the handle, substantially as shown and described.

2. The design for the handles of forks, spoons, &c., consisting in the gadroon scrolls *a*, scrolls *b*, leaf-scrolls *b'*, the raised surface ornamentation consisting in leaf-patterns *c c'*, and the shell-scroll pattern *d d'*, and the shell ornament *e*, and the interwoven bands *i*, substantially as shown and described.

Signed by me this 6th day of April, A. D. 1888.

GEO. W. SHIEBLER.

Witnesses:

GEO. T. PINCKNEY,
WILLIAM G. MOTT.
